OIL-BURNER AND SUPPORT THEREFOR

Horace E. Hopkins, Jeffersonville, Ind.

Application August 8, 1949, Serial No. 109,211

4 Claims. (Cl. 126—93)

(Granted under Title 35, U. S. Code (1952),
sec. 266)

1

The invention described herein, if patented, may be manufactured and used by or for the Government for governmental purposes without the payment to me of any royalty thereon.

This invention relates to burners for liquid fuel burning stoves for heating enclosures and among other objects aims to provide a burner which is easily manufactured, assembled on the stove and disassembled, which is easily cleaned, is safe, is of few parts and is supported in a unique manner so that there is no interference with the flames formed during combustion. Other objects and advantages will appear from the following description of embodiments of the invention shown in the accompanying drawings, in which—

Fig. 1 is a fragmentary side elevation of a heating stove equipped with the burner of the invention, a wall of the stove being broken away;

Fig. 2 is an enlarged sectional elevation of the burner and its supporting tube, the fuel tube being broken away;

Fig. 3 is a top plan view of the burner assembly of Fig. 2;

Fig. 4 is a top plan view of the burner base per se;

Fig. 5 is a top plan view of the burner top per se; and

Fig. 6 is a detail in elevation showing another form of support for the burner.

Referring particularly to the drawings, the burner of the invention is particularly designed for use with heating stoves adapted for tents, Quonset huts and similar enclosures. Such stoves may have an elongated hollow steel body 10 supported by two legs 11 (only one of which is shown), the stove body being connected on its interior and midway its ends with a vertical stove-pipe 12 which rests on the floor to provide a third leg for the stove and extends upwardly through the roof of the enclosure (not illustrated) to the exterior. The hollow stove body 10 is shown as rectangular with two elongated sides 10^a, two end walls 10^b (only one of each being shown) and a flat top 10^c provided with a round air opening 13. In this round opening the burner of the invention is positioned in such a manner that air is admitted freely to the interior of the stove body 10 to make possible efficient combustion of liquid fuel delivered to the burner by gravity from a fuel pipe 14. A needle valve 14a (preferably provided with a sight opening) connected to fuel pipe 14 controls flow of the fuel, which is contained in an elevated tank coupled to the needle valve, as will be understood without illustration.

To support the burner, a vertical tubular stand-

2

ard 16 with a chamfered lower end fits snugly over a stud 17 which is welded or otherwise securely fastened in an upright position to the bottom 10^d of the stove body, and at its upper end standard 16 is screwed into a boss 18 projecting centrally from the bottom of the burner base 19. The burner base is thus rigidly but removably attached to the standard, which in turn is rigidly supported by the stove body, yet may be lifted off the stud 17 at any time.

The burner base 19, which may be of cast iron, consists of a generally circular flat plate provided on its upper face with a central shallow recess 20, several concentric circular grooves 21, 22, 23, all of the same depth and surrounding recess 20, and an outer channel or channels 24 which are lower than the bottoms of the grooves and are bounded by arcuate upstanding lips or flanges 25. At diametrically opposite points on the burner base, two pairs of parallel ears 26, 27 are provided to aid in holding the burner top 28, each pair of ears having aligned apertures 29 to receive a cotter pin 30 passing through apertures 31 in the burner top. The burner top may be an aluminum casting and preferably is in the form of a circular plate flat on the underside and having four ribs 32 each upstanding from and integral with the top of the plate and lying at 90° to the ribs on either side, each rib terminating in an upstanding finger 33 and being provided with an aperture 34 below the finger. A tapped boss 35 is disposed centrally of the burner top to provide a connection for fuel pipe 14 and a fuel inlet or port 35 extends vertically through the boss directly above the shallow recess 20, the burner top 28 being held spaced a short distance (perhaps one eighth to one quarter of an inch) above the upper face of burner base 19 to provide a flat open area in which the fuel may flow and ignite. The cotter pins 30 serve to hold the burner top and base in proper spaced relation. It will be noted that either pair of diametrically opposite ends of ribs 32 may be united to the burner base by the cotter pins 30 and perforated ears 26, 27. By the described construction the standard 16 supports the burner in a horizontal position and substantially immovably within the round opening 13, with the four fingers 33 extending above the plane of the flat top 10^c of the stove.

To position the burner assembly, the standard 16 and the burner base and top may be united, then inserted from above through the air opening 13 and the standard then engaged with the stud 17. The fuel pipe may also be united to the burner prior to such positioning, after which it is coupled to the fuel supply. When dismantling

the burner assembly, the fuel pipe will be disconnected first and then the cotter pins will be withdrawn, permitting the burner top to be taken off by lifting two of the fingers 33. Then the burner base is exposed for inspection or cleaning. The complete burner and its standard 16 may of course be removed as an assembly by merely lifting out, after disconnecting the fuel line.

The fuel drops down from the needle valve and fuel pipe onto the bottom of the shallow recess 20, then flows into and over the several concentric grooves 21, 22, 23 and finally reaches the outer channel 24. Combustion takes place in the flat open space between the burner top and base. Air flows into the interior of the stove through the opening 13 and between the fingers 33, there being ample space thus provided for efficient combustion as the burner is wholly below the opening except for the tips of the fingers, as shown in Fig. 1. A pivoted damper or air valve 36 may be swung horizontally over the top of the stove partially to close the air inlet during mild weather or completely close it when the burner has been removed, and a latch 37 fixed to the stove top will fit over the damper to lock it when it is swung to closed position. The outer vertical edges of the fingers barely clear the edges of the air opening 13 so that if the burner is tipped even slightly one of the fingers will engage the edge of the air opening to prevent further tipping. Thus the comparatively small base offered by the standard 16 is a satisfactory support for the burner.

In lieu of the tubular standard 16, a solid rod 40 (Fig. 6) may be employed, said rod having a reduced lower end 41 which extends through an aperture 42 in the bottom 10^d of the stove body, with the shoulder formed by the reduced lower end 41 resting on the bottom 10^d as shown. The upper end of rod 40 may be secured to boss 18. This construction is advantageous if it is desired to have no obstruction on the interior of the stove body such as would interfere with cleaning.

It will be particularly noted that the location of the standard (16 or 40) in the center of the burner and extending straight down, plus its small lateral dimension, insure no interference with or deflection of the flames of combustion, which are free to extend outwardly from the periphery of the burner in all directions. Only the two pairs of ears 26, 27 slightly obstruct the flames and these are of the proper design to withstand the heat and present very little hindrance to the flow of air and free combustion. Either standard 16 or 40 is prevented from shifting laterally on the stove bottom by the means which supports it at its lower end; however both standards are readily lifted off the stove bottom and as readily replaced.

While embodiments of the invention have been described in considerable detail, the invention is not limited to the details of the disclosure but may assume a variety of other forms.

Having described my invention, what I claim as new and desire to secure by Letters Patent is:

1. In combination with a stove body having a bottom and a top, the top being provided with an air inlet; a burner having a base and a top secured to and slightly spaced from the base; means supporting the burner within the stove body just below the air inlet; said means comprising a relatively thin elongated standard secured at its upper end to the underside of the burner base at its center and adapted to be supported at its lower end directly upon the stove bottom; means on said stove bottom co-operating

5 with said standard to hold the standard in an upright position with lateral shifting upon the stove bottom made impossible, said means however permitting detachment of the standard therefrom by mere lifting of the standard; and liquid-fuel-delivering means disposed above the burner and discharging the fuel by gravity centrally of the burner into the space between the top and the base so that the fuel may flow from the center of the base in all directions toward the perimeter of the base.

10 2. In combination with a heating stove having a bottom; upstanding means fixed to the stove bottom; a tubular vertical standard fitting over but removable from the upstanding means and having screwthreads on its upper end; a burner base screwed at its center to the upper end of the standard; a burner top secured to the burner base in spaced relation thereto; and liquid-fuel-delivering means connected to the burner top and adapted to discharge fuel by gravity into the space between the burner top and base; the standard constituting the sole support for the burner and in turn receiving its sole support from the stove bottom.

15 3. In combination with a heating stove having a body with a bottom and a top, the top being provided with an opening providing an air inlet; a burner for liquid fuels adapted to be introduced into the stove body through said air inlet; burner-supporting means consisting of a straight standard secured at its upper end to the underside of the burner, the lower end of the standard having a reduced extension fitting an aperture provided in the bottom of the stove; the burner being supported by the standard just below the air inlet so that air may freely enter the interior of the stove body; a plurality of upstanding fingers on the burner which, when the burner is in position, extend upwardly through the air inlet and may contact the edges of the air inlet in the event of tilting of the burner on its support; and liquid fuel delivery means discharging by gravity into the burner at the center thereof.

20 4. In combination with a burner having an open area between its top and bottom in which liquid fuel may flow; means discharging liquid fuel to said open area; a relatively thin upright burner-supporting member; means to detachably secure the upper end of the upright supporting member to the middle of the underside of the burner, the lower end of the upright supporting member being adapted to be supported on the bottom of a stove; and upstanding fingers fixed 25 to the burner top at the perimeter thereof and adapted to engage or be slightly spaced from the horizontal edges of an opening in the top of the stove.
